Inventor

Julia M. Murray

By Cornwall, Readell & Janus, ATTYS.

UNITED STATES PATENT OFFICE.

JULIA M. MURRAY, OF ST. LOUIS, MISSOURI.

NECKLACE BRACELET.

Application filed October 10, 1924. Serial No. 742,922.

My invention relates to articles adapted to be used for necklaces and bracelets and similar ornamental purposes or may be embodied in rosaries or other articles of similar form 5 whether used for ornamental purposes or otherwise.

The object of my invention is to provide a chain or strand adapted to form a single loop, such as may be used for necklace or 10 like purpose and also adapted to form a plurality of smaller loops forming a bracelet or like structure.

My invention includes an endless chain having a clasp element and cooperating elements at intervals in the chain and preferably forming a part thereof which are readily secured to or detached from the clasp element.

In the accompanying drawings illustrating a preferred embodiment of my invention, I show the same comprising a rosary made in the form of a necklace with a crucifix pendant. The rosary is also adapted to be formed into a plural-loop bracelet in 25 which the crucifix forms a portion of a clasp securing the individual loops. In these drawings—

Figure 1 is an elevation of the article in necklace form.

30 Figures 2 and 3 are top and side views, respectively, of one part of the clasp element.

Figure 4 is a top view of the other part of the clasp element.

35 Figure 5 is substantially a diagrammatic showing of the method of forming a bracelet out of the necklace.

Figure 6 is a view of the bracelet so formed as applied to the wrist of the wearer.

40 The main portion of the necklace as shown in Figure 1 comprises a series of relatively short strands 1, 2, 3, 4, and 5 permanently assembled end to end to form a single long strand or chain, the lower ends

45 of which are permanently connected by attachment to a common engagement element 6, here shown as a disk. This element preferably will bear an image of the Virgin and will form a scapular medal. Upstanding

50 posts 7 are mounted on element 6 and each post has an annular boss or enlargement 8 near its outer end. Each strand 1, 2, 3, 4 and 5 may include ten beads 9 to form a decade and in between each of the strands of

55 beads 9 I place an isolated bead 10 and on each side of bead 10 I insert a link 11 large

enough to slip over projections 7 on the element 6. While this is a preferred arrangement, if desired each of the links of the necklace could be made large enough to slip over projections 7. It will be understood that the beads and chain or other elements connecting the beads and links 11 may be of any well-known structure, and do not form any part of my present invention. 60 65

The cross 12, secured to element 6 by a pendant chain 13, consists of a substantially heavy rigid body portion and relatively thin spring-like parts 14 which are perforated at 15 and slit at 16 to form spring elements adapted to slip over the upper ends of projections 7 and engage bosses 8 to retain the crucifix on element 6, thereby forming a two-part clasp which retains the ends of each strand 1, 2, 3, 4 and 5 when the latter are arranged as shown in Figure 5 so that the ends of each strand engage the projections 7. It will be understood that the cross 12 will bear an image of Christ and will constitute a crucifix. 70 75 80

It will be seen that the article described may be worn as a necklace or may be wrapped around the wrist of the wearer to form a plural-loop bracelet. The change from one form of jewelry to the other is 85 easily made, in the one case by looping the strands 1, 2, 3, 4 and 5 about the wrist and engaging projections 7 and applying the upper portion of the clasp thereto and in the other case by merely releasing the clasp and 90 permitting the detachably secured ends of the strands to separate from the clasp element 6.

Obviously, element 6 will be made decorative and, of course, my invention is not 95 limited to the rosary embodiment illustrated, but may consist in any attractive arrangement of beads, links and pendants or other ornamental elements.

I claim:

1. In an article of the class described, an ornament, a second ornament, means suspending said second ornament from said first-mentioned ornament, a projection on one of said ornaments, an element on the other of said ornaments adapted to yieldingly engage said projection, and a long strand of permanently assembled elements secured at its ends to one of said ornaments and provided intermediate its ends with a link member for receiving said projection and permitting the latter to extend through 105 110

the member to engage said engaging element.

2. In a religious article, a continuous strand of rosary beads, a scapular medal to which the ends of the strand are secured, a plurality of projections on said medal, an element in each decade of said strand of rosary beads having an opening whereby the element may be placed over one of said projections, a crucifix applicable to said medal and having openings for yieldingly receiving said projections, when the latter engage said elements, to hold said elements in engaged position whereby the article may 10 form a plural loop bracelet.

3. In an article of the class described, an ornament, a second ornament adapted to be placed over said first mentioned ornament, flexible means securing said ornaments to each other, a closed strand of flexible structure attached to one of said ornaments and having restricted portions adapted to be placed between said ornaments, and elements on said ornaments adapted to interengage each other to secure said portions of said strand in position between said ornaments. 20

In testimony whereof I hereunto affix my signature this 29th day of September, 1924.

JULIA M. MURRAY.
